(57) **CLAIM**

(30) **Foreign Application Priority Data**

The ornamental design for a beam support bracket, as shown and described.

Sep. 11, 2009 (EM) 001163935-0006

(51) **LOC (9) Cl.** **08-05**

DESCRIPTION

(52) **U.S. Cl.** **D8/380**

FIG. 1 is a front/top side perspective view of the beam support bracket according to my design;

(58) **Field of Classification Search** D8/382,

FIG. 2 is a left side view with the top side oriented up thereof;

D8/381, 380, 373, 360, 359, 358, 354, 349;
D3/24; D15/5, 199, 147, 138; 474/7, 66,
474/52, 47-53, 29, 198, 196, 161; 315/15;
248/638, 636, 250, 235, 200; 242/532.6,
242/530.3, 476.6, 118.6; 239/197; 160/315;
137/355.26, 355.2, 355.19, 355.16; 108/157.13,
108/147.12-147.17

FIG. 3 is a front view with the top side oriented down thereof;

See application file for complete search history.

FIG. 4 is a right side view with the top side oriented to the right thereof;
